KNITTING MACHINE

Robert H. Lawson, Pawtucket, R. I., assignor to
Hemphill Company, Central Falls, R. I., a corporation of Massachusetts

Application February 3, 1934, Serial No. 709,545

4 Claims. (Cl. 66—125)

This invention relates to improvements in knitting machines, the drawings and the following description disclosing the invention as being applied to a so-called flat or full-fashioned knitting machine although the invention is applicable to other types of knitting machines.

In the drawings:

Fig. 1 is a view in end elevation of a so-called flat knitting machine showing how the invention is applied thereto;

Fig. 2 is a detail view of the thread marking device shown in Fig. 1;

Fig. 3 is a plan view of the mechanism shown in Fig. 2;

Fig. 4 is a fragmentary sectional view taken on the line 4—4, Fig. 3; and

Fig. 5 is a fragmentary view in side elevation similar to Fig. 1 but showing a modification.

Referring particularly to Figs. 1, 2, 3 and 4, the frame 1 of the knitting machine has mounted thereon a needle bar 2 in the usual manner, the said bar having fixedly mounted therein spring beard needles 3 as is usual in full-fashioned machines. Also fixedly mounted upon the frame 1 is a sinker carrying bar 4 having sinkers 5 slidably mounted therein. Mounted above the needle and sinker bars are guides such as 6 for feeding threads such as 7 to the sinkers in the usual manner by moving back and forth across the frame longitudinally of the needles and sinkers. From bobbins 8 the threads 7 pass to the guides 6 through a thread marking mechanism 9 being lightly tensioned as by means of springs 10.

As shown, a thread 7 is led from the source of supply such as a bobbin 8 through porcelain or other eyelets 11 provided in arms 12 upstanding from a plate 13 rigidly mounted upon a bracket 14 as by means of screws 15. The bracket 14 projects laterally from the machine frame being connected thereto as by means of screws 16. Between the eyelets 11 and connected to the plate 13 as by screws such as 17 is a circular receptacle 18 having holes 19 and 20 for the passage of the thread 7 therethrough. Within the receptacle 18 are plates 21, 22 which are disposed in parallel relation and between which and the opposite inner walls of the receptacle 18 is a wick 23 of absorbent material, which is supported upon a pin 23' connected to receptacle 18, as well as a quantity of marking liquid 24 which may be a transient dye, i. e., one that will be washed out or disappear during the finishing of the stocking. Normally the thread 7 passes through the holes 19 and 20 being under sufficient

tension to be maintained above the wick 23; however, at predetermined times as determined in a manner hereinafter to be described, the thread 7 is depressed downwardly to the position shown in Fig. 4 where it is in contact with the wick 23. This contact of the thread with the wick is momentary with the result that the thread is periodically spotted with the transient dye for a purpose hereinafter to be more clearly set forth.

The hereinbefore described movements of the thread 7 in contact with the wick 23 are effected by means of an L-shaped bar or rod 25 which is automatically movable to and from the full and dotted line positions of Fig. 2. The rod 25 is adjustably connected as by a screw 26 to a collar 27 which latter is in turn adjustably mounted on a rod 28 as by means of a set screw 29. The rod 28 extends downwardly through a hole in plate 13 the lower end of the rod 28 being pivotally mounted as at 30 to one end of a lever 31 pivoted at 32 to the machine frame. Intermediate its ends the lever 31 has attached thereto a cam or follower 33 which is periodically engaged by a cam or cams on a drum 34, the latter being driven in any convenient manner as by means of a belt 35 so that the lever 31 is rocked once each course of knitting, i. e., twice during the complete back and forth reciprocation of the yarn guides and slurcock.

The rod 28 is elevated by cams on the cam drum 34 as just described and is lowered to the position shown in Fig. 1 by means of a coil spring 36 which at one end engages the lower face of the plate 13 and at its other end engages collar 37 adjustably fastened to the rod 28 as by means of a set screw 38. Another collar 39 is adjustably fastened to the upper portion of the rod 28 as by means of a set screw 40, the collar 37 serving to compress the spring 36 upon the rod 28 being elevated by the cam drum 34, and the collar 39 serving to limit the downward movements of the rod 28 due to the expansion of the coil spring 36. The lowering of the rod 28 as by means of the spring 36 causes the guide or follower 33 to drop off a cam or cam drum 34 where it rests until further rotation of the drum 34 again elevates the rod 28 to the full line position shown in Fig. 2. The lowering and subsequent raising of the rod 28 effects a marking of the thread, the rod 25 pushing the thread 7 into momentary contact with the wick 23.

During the knitting of full-fashioned stockings or other fabric the slurcock or sinker cam follows the transverse movements of a yarn guide or guides and causes the sinkers to sink or

measure the yarn around the shanks of needles in both directions of reciprocation. If the sinker cam face effective during reciprocation in one direction becomes worn more than the cam face 5 effective during reciprocation in the opposite direction, the first cam face fails to measure off as much yarn as is measured by the cam face second mentioned, the result being that during alternate courses tighter stitches are knitted 10 than during intervening courses giving to the fabric a so-called "wash-board" appearance. The objection may be overcome by the marking mechanism hereinbefore described, which provides a convenient means for readily detecting when the 15 yarn is not being knitted uniformly. Assuming the yarn guide to have reached the limit of its traverse in one direction and to have stopped momentarily, Fig. 1, the marking mechanism is brought into contact with the yarn 7, the rod 25 20 being immediately thereafter elevated. Now further assuming that during the next reciprocatory movement of the yarn guides and slurcock that the mark just made on the yarn 7 is moved to the position indicated at 41, Fig. 1, as the yarn 25 is measured for the next course of knitting, the distance between the marking mechanism 9 and the point 41 measures the amount of the yarn 30 knitted during the said course. As the yarn guide comes to rest at the opposite end of the bank of needles, the marking mechanism is again 35 actuated to mark the thread after which the thread guide 6 moves in a direction opposite to the direction first mentioned. If the cam surface effective during the last mentioned movement of 40 the yarn guide and slurcock has been somewhat worn away, the same length of yarn as before will not be knitted, the result being that the last marking will move only to the position such as that indicated at 42. Consequently, by noting 45 where the markings 41, 42 stop while the yarn guide is momentarily at rest the operator of the machine can readily determine whether uniform fabric is being knitted and, furthermore, can at once determine which stroke of the yarn guides 50 and slurcock is causing the greatest amount of yarn to be knitted, after which the operator can effect adjustment or replacement of the sinker cam.

Referring to Fig. 5, there is shown a mechanism indicated generally by the numeral 43, which is mounted on the bracket 14 and which draws sufficient thread preparatory to each course of knitting sufficient for the knitting of that course, and thus avoids unevenness in the 55 knitted fabric which frequently results from frequent changes in the yarn tension due to the thread tending to stick or adhere to a cone 8 at certain places in the cone winding.

Attached to the bracket 14 in any convenient 60 manner is a supplemental bracket 44 upstanding from which are a series of lugs 45, 46 having eyelets therein through which a thread 7 passes. Between the lugs 45 and 46 there is an upstanding bracket 47 pivotally carrying a clamp 48, a 65 spring 49 normally maintaining the said clamp 48 in engagement with the thread 7. Thus the clamp 48 prevents movement of the thread 7 in the direction of the cone 8 but permits the thread 7 to pass freely in the opposite direction. Between the lugs 45 are rods 50 which are adjustably and fixedly carried by a plate 51 and at their upper ends pass through holes in the bracket 44, the said upper ends being provided with holes or notches receiving the thread 7. The intermediate rod 50 is elongated extending down-

wardly as at 52 and being pivotally connected at 53 to a lever 54 which may be pivotally supported as is the lever 31, cams on the drum 34 periodically rocking the said lever 54. Between the lugs 46 are rods 55 which are adjustably and fixedly carried by a bar or plate 56 and pass upwardly through holes in the bracket 44, said rods 55 having holes or notches in their upper ends to receive a thread 7. The intermediate rod 55 is elongated extending downwardly as at 57, the lower end thereof being pivoted at 58 to a lever 59. The lever 59 may be pivotally mounted as is the lever 31 and is periodically actuated by cams carried by the drum 34.

At the end of each reciprocatory movement of the thread guides, they are momentarily at rest and at such time the lever 59 is actuated to move the rods 55 to the elevated position shown in Fig. 5, which draws sufficient thread for the next course through the clamp 48. Preparatory to the aforesaid movement of the lever 59, the lever 54 is rocked to move the rods 50 from the position shown in Fig. 5 to a relatively elevated position such as that of the rods 55. The movement of the rods 50 causes thread to be drawn from the source of supply, i. e., a bobbin 8, the clamp 48 preventing thread from being drawn back, i. e., to the left, Fig. 5. Obviously the needles knit an amount of yarn determined by the loop measuring instrumentalities such as the sinkers, and the extent of the upward movement of the rods 50, 55 is immaterial so long as sufficient thread is drawn from the source of thread supply to provide enough slack in the thread to permit the knitting of the ensuing course without the sinkers being required to draw additional thread from the source of thread supply and through the clamp 48.

The mechanism shown in Fig. 5 for pulling thread from the source of supply thus avoiding 40 unevenness in the knitted fabric, may be combined with a mechanism such as that shown in the remaining figures of the drawings.

The objections hereinbefore specifically noted which are overcome by using the mechanisms shown in the drawings hereinbefore disclosed, are cited merely by way of example.

Although in the foregoing description, full-fashioned knitting has been specifically mentioned, it is not the intention thereby to limit 50 the invention to full-fashioned knitting as, obviously, the invention is equally applicable to circular knitting as where reciprocatory movements of a needle cylinder effect the knitting of split fabric. Furthermore, the invention can be applied to so-called Burson or flat independent 55 needle knitting machines.

I claim:

1. A knitting machine including needles and sinkers, the said sinkers being adapted to measure stitches around the shanks of the needles, yarn feeding means adapted to reciprocate along the needles and sinkers for feeding yarn thereto, periodically actuated means adapted to mark the yarn at different places along the length thereof, thereby indicating to the operator of the knitting machine whether uniform fabric is being knitted.

2. A knitting machine having needles and sinkers and yarn feeding means, there being 70 relative reciprocatory movements between the yarn feeding means and the needles and sinkers, periodically actuated means adapted to mark the yarn at different places along the length thereof, thereby indicating to the operator of 75

the knitting machine whether uniform fabric is being knitted.

5. 3. A means for marking yarn in a machine for the purpose of indicating whether or not the yarn is being fed uniformly, said marking means including an automatically actuated member normally out of contact with the yarn but when actuated moved into engagement with the yarn for the purpose of marking the same.

4. In a knitting machine having needles and yarn feeding means for the needles reciprocating relatively thereto, a yarn supply and means interposed between the supply and needles for imparting to the yarn and at spaced points along 5 the length thereof certain visible indications.

ROBERT H. LAWSON.
